UNITED STATES PATENT OFFICE.

EUSTACE CREEES AND CHARLES S. COURT, OF PROVIDENCE, RHODE ISLAND,
ASSIGNORS TO HENRY H. CURTIS & CO., OF NORTH ATTLEBOROUGH,
MASSACHUSETTS.

DESIGN FOR A BACK FOR BRUSHES OR SIMILAR ARTICLES.

SPECIFICATION forming part of Design No. 31,273, dated July 25, 1899.

Application filed June 28, 1899. Serial No. 722,291. Term of patent 3½ years.

To all whom it may concern:

Be it known that we, EUSTACE CREEES and CHARLES S. COURT, citizens of the United States, residing at Providence, in the State of Rhode Island, have invented and produced a new and original Design for the Backs of Brushes or Similar Articles, of which the following is a specification, reference being had to the accompanying drawing, forming part thereof.

The drawing shows a view of the back of a brush having a curved outline and provided with our new and original design, the leading or material features of which consist in the terminal flower *a*, the oppositely-foliated scrolls *b b*, and the intermediate shield *c*, with the flower *d* at the upper end of the foliated scrolls, the branching foliated scroll *e*, the shield *g*, located above the base of the branch-

ing foliated scroll *e* and between the reversely-foliated scrolls *h h*, the terminal ornament *i*, the reversely-foliated scrolls *j j*, the shield *k*, the reversely-foliated scrolls *l l*, the flowers *m m*, and the central bunch of flowers *n*.

It is apparent that this design for the backs of brushes is also adapted for the backs of similar articles.

Having now described our new design, what we claim as new, and desire to secure by Letters Patent, is—

The design for the back of a brush or similar article, as herein shown and described.

EUSTACE CREEES.
CHAS. S. COURT.
